UNITED STATES PATENT OFFICE.

HENRY A. ZIOLA, OF TOLEDO, OHIO, ASSIGNOR TO THE SWARTZBAUGH MANUFACTURING COMPANY, OF TOLEDO, OHIO, A CORPORATION.

MULTIPLE HEAT ELECTRIC COOKER.

Application filed May 20, 1926. Serial No. 110,496.

The present invention relates in general to electric cookers, and more particularly to a device of this character which embodies novel features of construction, whereby different temperatures may be obtained selectively at will.

Among the further objects of the invention are to provide a variable heat electric cooker in which the different heats are obtained by the use of the same potential the device being adapted to be designed so that it can be operated on the usual electric light circuit of 110 or 120 volts or other voltages.

The invention also contemplates a variable heat electric cooker in which the necessity of using a switch to obtain different heats is avoided, the desired result being obtained by plugging in at different places and connecting the main circuit to different terminals.

While one particular embodiment of the invention will be shown and described for illustrative purposes, it will be understood that many modifications and changes can be made in the details of construction without departing from the spirit thereof.

For a full understanding of the invention reference is to be had to the following description and accompanying drawings in which,

Figure 1 is a vertical sectional view through a variable heat electric cooker which is constructed in accordance with the invention.

Figure 2 is a transverse sectional view through the same on the line 2-2 of Figure 1.

Figure 3 is a side elevation of a portion of the exterior of the cooking well showing the terminal supports for the resistance wires, portions being broken away to illustrate more clearly the details of construction.

Figure 4 is an enlarged longitudinal sectional view taken on the line 4-4 of Figure 3.

Figure 5 is an enlarged sectional view through the socket, showing the three contact pins and the plug which is adapted to be selectively applied thereto in different positions.

Figure 6 is a wiring diagram.

Figure 7 is a vertical sectional view of a modification of the invention.

Figure 8 is a horizontal sectional view

through the modified form of cooker of Figure 7.

Corresponding and like parts are referred to in the following description and indicated on all of the views of the drawings by like reference characters.

The outer shell or casing of the cooker can be constructed in any desired manner, although for illustrative purposes it is shown as comprising a main cylindrical section 1, which has a bottom section 2 connected to the lower edge thereof and a top section 3 connected to the upper edge thereof. The top section is in the form of a ring and supports a cooking well 4 which has its upper end secured thereto. The cooking well is spaced from the outer shell and the space is preferably filled with some heat insulating material such as mineral wool 5. The food to be cooked is placed in the cooking well 4 and the cooker closed by means of a cover 6 which is applied to the upper end of the cooking well. The cover may have the usual handle 7 applied thereto, and where the device is portable a conventional bail 8 may be connected to the outer casing.

A sheet of asbestos or similar material is wound around the exterior of the cooking well 4 to provide an insulating cover of suitable thickness. As shown on the drawings there are two thicknesses of asbestos 9 extending around the periphery of the well.

Two resistance wires 10 and 11, respectively, are wound around the asbestos 9 in helical form, each turn of one of the wires being located between two turns of the other wire. The two resistance wires are thus separated from each other and wound over a large portion of the area of the cooking well so that the heat from the resistance wires will be evenly distributed. In order to bring about a more even distribution of the heat the convolutions of the resistance wires at the middle of the cooking well are spaced a considerable distance apart, as indicated on the drawings, because there is less loss of heat by radiation at the middle of the cooking well than at the end portions thereof. After the resistance wires have been wound around the insulating layer 9, they are covered with a plastic cement 12 of a character which is well known in the art. The resistance wire 10 is of greater diameter than the resistance wire 11, so that it will offer less resistance

to the passage of electric current than the smaller diameter wire 11 and become heated to a higher degree of heat than the latter wire, when the same voltage is applied.

5 A metallic strip 13 is arranged under the insulating covering 9 and extends longitudinally of the cooking well. The upper and lower ends of the metallic strip 13 are engaged by screws 14, by means of which an upper lava insulating block 15 and a lower lava block 16 are held in position. A screw 17 extends transversely through the upper lava insulating block 15 and holds a terminal plate 18 in position thereon. The upper 10 ends of the two resistance wires 10 and 11 are secured to the terminal plate 18 by means of a screw 19, while an insulated terminal wire 20 is secured to the plate 18 by a second screw 21. The lower lava insulating block 16 is formed with a pair of transverse openings through which the lower ends of the respective resistance wires are threaded.

The outer shell is provided at the bottom thereof with a socket 23. A lava insulating block 24 is arranged at the inner end of the socket and three terminal stems 25 project from the said lava insulating block 24 into the socket. As is indicated more clearly by the wiring diagram, the lower end of the 20 resistance wire 11 is connected to the end terminal stem 25, while the lower end of the resistance wire 10 is connected to the intermediate terminal stem 25 and the lower end of the terminal wire 20 is connected to the 25 other end terminal stem 25. The plug 26, by means of which connection is made with the electric circuit, is of a conventional construction, being adapted to engage two of the terminal stems 25. It will be understood 30 that it can be applied to the intermediate terminal stem 25 in combination with either of the end terminal stems. When the plug is applied in one position, the electric current is caused to pass through the resistance wire 40 10 without passing through the resistance wire 11, and the heavy wire is then heated to produce a high temperature heat. When the connecting plug 26 is applied to the other pair of terminal stems, it will be obvious that 45 the electric current flows through both of the resistance wires in series, so that a low heat is obtained. The same potential is used, however, for obtaining the high heat or the low heat. It might, of course, be arranged so 50 that the current would pass through the fine wire alone to obtain a low heat and through the larger gauge wire alone to obtain the high heat, although it has been found that more economical results are obtainable where 55 the current is permitted to pass through both of the resistance wires in series when the low heat is desired.

The two resistance wires 10 and 11 are preferably of the same length so that they 60 make the same number of turns around the

cooking well. Where the usual 110-120 volt electric lighting circuit is to be used it has been found that good results can be obtained by using a sufficient length of #21 gauge wire to give a resistance of 31 ohms, and a 70 sufficient length of #26 wire to have the resistance of 98 ohms. About 38½ feet of each length of wire will be required, and when both units are in series the combined resistance will be 129 ohms. When the high heat 75 is on approximately 400 watts at 120 volts will be used, while when the low heat is on approximately 100 watts will be used. The high heat can be employed for starting water to boil or initially heating the contents of the 80 cooking well, while after the water has reached the boiling point or the contents of the cooking shell have been thoroughly heated, the low heat will be sufficient to continue the cooking operation without danger of 85 burning the contents of the cooker.

The reason both the No. 21 and 26 resistance wires are used in series for a low heat is because the total of the 129 ohms is thus obtained, and the No. 21 resistance 90 wire is made to function for both the low heat and high heat connections. An additional 31 ohms is obtained by using the No. 21 gauge in series with No. 26 gauge (of 98 ohms) making a total of 129 ohms, although as stated previously the No. 26 gauge resistance wire could be used alone for the low heat connection, although there is economy in using both of the resistance wires in series for the low heat connection. 95

A modification is indicated by Figure 7, the mineral wool or other packing interposed between the cement 12 and the outer wall 1 being omitted. An open space is left between the outer wall and the cement, 100 it having been found that under many conditions the open space will provide a proper heat insulation for the inner receptacle. 105

It is obvious, of course, that instead of winding the two resistance wires helically 110 around the cooking well with the convolutions of one resistance wire arranged between the convolutions of the other resistance wire, the two resistance wires may be wound in superposed layers with insulating 115 material between the same, or the two resistance wires may be wound around different portions of the cooking well.

Moreover in this particular construction the lava or insulating blocks 15 are attached 120 to a metal member or cylinder which surrounds the cooking well 4, instead of being secured by a metallic strip 13. In other words, there is provided the reinforcing cylinder 30 which performs two functions, 125 namely provides first a reinforcing packing for the cooking well and secondly it forms an attaching member equivalent to the metal strip or plate 13 previously described. As regards the omission of the mineral wool 130

or packing, as above set forth, I have found that under certain conditions the non-use of the insulating packing affords advantageous results. Of course, when the cylinder 5 30 is provided it is surrounded by the layer of asbestos 9 directly applied thereto instead of to the cooking well 4.

Having thus described my invention what I claim as new and desire to secure 10 by Letters Patent is:

1. An electric cooker including a cooking well, a layer of insulating material extending around the same, a strip under the insulating material, a resistance wire wound 15 around the insulating layer, and blocks of insulating material connected to the strip, said blocks of insulating material serving to engage the ends of the resistance wire.
2. An electric cooker including a cooking well, a layer of insulating material upon the well, a strip extending under the insulating layer, a plurality of resistance wires wound upon the insulating layer, insulating blocks connected to the before mentioned strip and supporting the terminals of the resistance wires, and means for selectively connecting the main current to the resistance wires to obtain different degrees of heat.
3. An electric cooker including a cooking well, a layer of insulating material extending around the well, a strip arranged under the insulating layer, a plurality of resistance wires wound upon the insulating layer, 20 insulating blocks at the end of the strip, fastening members extending through the insulating layers and securing the blocks to the strip, the ends of the resistance wires being supported by the blocks, and means 25 for selectively connecting the main current to the resistance wires in order to obtain different degrees of heat.
4. An electric cooker including a cooking well, a layer of insulating material extending around the well, a strip arranged under the insulating material, a pair of resistance wires wound helically around the insulating layers with the convolutions of 45 one resistance wire received between the convolutions of the other resistance wire, insulating blocks supported by the strip, a

terminal member on one of the insulating blocks to which the two resistance wires are connected, the other insulating block supporting the ends of the resistance wires independently, and means for selectively causing the main current to pass through one of the resistance wires or through the two resistance wires in series to obtain different degrees of heat. 55

5. An electric cooker including a cooking well, a layer of insulating material extending around the cooking well, a strip extending under the insulating layer, a pair of resistance wires wound helically on the insulating layer with the convolutions of one resistance wire received between the convolutions of the other resistance wire, insulating blocks carried by the ends of the strips, a terminal plate mounted upon one 65 of the insulating blocks and having the ends of both insulating wires connected thereto, the other insulating block being formed with openings through which the 70 resistance wires are carried, and means for 75 selectively connecting the main electric current to the resistance wires in order to obtain different degrees of heat.

6. An electric cooker comprising a cooking well, a metallic member applied to said well, a layer of insulating material surrounding the well and said metallic member, resistance wire wound about the insulating layer, insulating blocks attached to the metallic member aforesaid, and terminal 80 means connected with said insulating blocks.

7. An electric cooker comprising a cooking well, a metallic member applied to said well, a layer of insulating material surrounding the well and said metallic member, resistance wire wound about the insulating layer, insulating blocks attached to the metallic member aforesaid, and terminal 85 means connected with said insulating blocks, the ends of the resistance wire being 90 connected with the insulating blocks so as to hold the resistance wire in place upon the insulating layer.

In testimony whereof I affix my signature.

HENRY A. ZIOLA.
